MERCHANDISE DISPLAY AND STORAGE STAND

Carl E. Lindgren, Rockford, John J. Racila, Chicago, and William Brunner, Wilmette, Ill., assignors to Amerock Corporation, Rockford, Ill.

Filed Mar. 11, 1970, Ser. No. 21,853

Term of patent 14 years

Int. Cl. D6—04

U.S. Cl. D80—9

FIG. 10

FIG. 10a

FIG. 10b

FIG. 4FIG. 5FIG. 7FIG. 6

FIG. 1 is a perspective view of a merchandise display and storage stand embodying our new design.

FIG. 2 is a front elevational view thereof.

FIG. 3 is an elevational view taken on the side opposite that shown in FIG. 1.

FIG. 4 is a cross-sectional view taken on line 4—4 of FIG. 2.

FIG. 5 is a cross-sectional view taken on line 5—5 of FIG. 2.

FIG. 6 is a rear elevational view thereof.

FIG. 7 is an enlarged cross-sectional view taken on line 7—7 of FIG. 2.

We claim:

The ornamental design for a merchandise display and storage stand, as shown.
